UNITED STATES PATENT OFFICE.

GEORGE H. GILMAN, OF BELMONT, MASSACHUSETTS.

WINCH.

Application filed March 26, 1921. Serial No. 455,927.

My invention relates to winches and particularly but not exclusively to a portable capstan for use in mines.

My invention will be best understood from the accompanying drawings and following description of a specific embodiment of my invention selected for illustrative purposes, while the scope of my invention will be particularly pointed out in the appended claims.

10 In the drawings:—

Figure 1 is a central sectional elevation of the submitted embodiment of my invention;

15 Figs. 2, 3, 4, 5 and 6 respectively are sections on the lines 2—2, 3—3, 4—4, 5—5 and 6—6 of Fig. 1; and

Figs. 7, 8 and 9 respectively are sections on the lines 7—7, 8—8 and 9—9 of Fig. 3.

In general, the submitted embodiment of my invention comprises a drum, its support 20 having means for attachment to a mine column and fluid operated mechanism for turning the drum.

Referring to the drawings, I have shown a drum 1 and for supporting it a pillar 3 having at its lower end the substantially frusto-conical projection 4 for engagement with an attachment 5 for securing it to a mine column or like support 6, the pillar being bored out to provide a cavity 7 affording a chamber for lubricant for the machine. Adjacent the lower end of the pillar is a flange 9 which supports the motor casing 11, the latter having a peripheral wall 13 and being closed by a diaphragm 15.

35 The motor as shown comprises a disk-like rotor 17 cooperating with rotary abutments 19 of similar shape, the rotor being provided with a series of gear teeth 21, the faces of which fit the interior surface of the peripheral wall of the motor casing, while the rotary abutments which fit other portions of the same surface are cut away to form the recesses 23 for meshing with these teeth. The rotor and abutments are so formed that

40 when the teeth have moved out of mesh with the recesses the cylindrical surfaces of the rotor and abutments are in contact. The upper and lower surfaces of the rotor and abutments in a fluid tight manner fit the under surface of the diaphragm 15 and the 45 interior bottom surface of the motor casing.

Motive fluid is supplied to the motor through a suitable intake connection 25, and herein the motor is controlled by the combined reversing and throttle valve 27 which I provide with an operating handle 28. This

valve which is generally cylindrical in shape is provided with the closed-ended axial bore 29 and the spaced passages 31 and 33 placing the bore in communication with the exterior surface of the valve, while in the same transverse planes as the passages 31 and 33 respectively are the arcuate passages 35 and 37 formed on the exterior surface of the valve, and the ports 36 and 38 formed in the wall of the valve casing for placing the interior thereof in communication with the atmosphere. In the bottom portion of the motor casing I form passages 39 and 41 opening into the valve casing and adapted to be placed in communication with the atmosphere or with the motive fluid supply by means of the valve 27, in such manner that when the passage 39 is connected to the atmosphere, the passage 41 is connected to the motive fluid supply and vice versa. As shown by Figs. 3, 7, 8 and 9, the passage 39 is supplied with motive fluid through the valve passage 33, while the passage 41 is placed in communication with the atmosphere by way of the arcuate groove 35 and port 36. If the valve is turned counter-clockwise from the position shown by Fig. 7, the supply of motive fluid to the passage 39 will be throttled, and if the turning is continued until the passage 33 is moved out of communication with the passage 39, the supply of motive fluid to the passage will be interrupted and if, from this position, it is turned still farther, the passage 39 will be connected to the atmosphere by means of the arcuate passage 37 and port 38, while the passage 41 will be supplied with motive fluid by means of the passage 31 of the valve, which will act to drive the motor in the direction opposite to that in which it is driven with the valve in the position shown by the drawings.

The passage 41 above referred to is provided with the branches 43 and 45 which respectively terminate in ports 47 and 49 opening into the motor casing adjacent the places of intersection of the rotor 17 with the abutments 19. Similarly, the passage 39 branches into the passages 51 and 53, respectively terminating in ports 55 and 57 which are located at the sides of the intersections opposite the ports 47 and 49. In the position of the parts shown, motive fluid entering the motor casing through the ports 55 and 57 acts to exert pressure on the abutments and teeth 21 in mesh therewith, thus

causing rotation of these parts, while after the teeth have moved out of mesh with the abutments, and while the latter continue to act as abutments to enable the motive fluid 5 acting on the teeth to move the rotor, the abutments are rotated by means hereinafter described to cause each tooth consecutively to engage one of the recesses in the side rotors. The motive fluid supplied through the 10 port 47 is exhausted through the port 55, and similarly the motive fluid admitted through the port 49 is exhausted through the port 57.

Surrounding the pillar adjacent the motor 15 is shown a roller bearing 59 for the sleeve 61 and to the latter is rigidly secured the rotor of the motor by means of a key 63. This sleeve extends through a suitable opening in the diaphragm and supports the pinion carrier 65 of an epicyclic reduction gear 20 of the planetary type. On the exterior surface of the carrier is formed a series of gear teeth 67 in mesh with pinions 69 secured by means of suitable keys 71 to shafts 73, the 25 latter being integrally connected with the abutments. The series of gear teeth 67 and those of the pinion 69 are of such number as to keep the abutments in proper rotative relation with the rotor. The shafts 73 are 30 supported in roller bearings 75 and 77, the latter being supported in the sleeve 79 provided with a flange 81, which projects into the motor casing and is received by the cut-away portion 83 of the diaphragm. In this 35 way, as the sleeve tightly fits the bore 85 formed in the diaphragm, it together with the flange 81 serves to dowel the diaphragm to the motor casing. Supported by the diaphragm 15 is a gear casing member 84, 40 having projections 86 receiving the roller bearings 75 for the shafts 73. For holding the gear casing member, the diaphragm 15 and the motor casing 11 in assembled relation to each other and to the flange 9, I have 45 shown the bolts 88.

It will be observed that both the rotor and abutments act to drive the carrier 65 and if desired I may omit the connection between the abutments and the carrier when 50 other means are employed for causing the rotor and abutments of the motor to revolve at proper relative speeds of rotation.

As illustrated by Figs. 1 and 4, adjacent the lower portion of the carrier is a fixed 55 annular series of gear teeth 87 formed on the disk 89 which is secured to the pillar by means of the key 91, and adjacent the opposite end of the carrier rotatably supported on the pillar is the gear 92 affording a series 60 of teeth 93. On the carrier 65 in parallel relation to the pillar is secured a pair of diametrically oppositely located spindles 95 on which are rotatably mounted sleeves 97 carrying an annular series of gear teeth 65 99 meshing with the series 93 and a series

101 meshing with the fixed series 87. The series 101 and the series 87 in mesh therewith are respectively of such pitch diameter that they form a gear set of slightly different ratio than the gear set afforded by the 70 annular series of teeth 99 in mesh with the series 93. In this way, when the motor is in operation, the annular series of gear teeth 101 is rolled around the series 87 which causes the series 99 to rotate the series 93 75 at a speed much less than that of the rotor. This construction provides a compact machine by reason of the fact that sufficient power for operating the drum may be secured by a high speed motor, the size of 80 which for a given output is inversely proportional to its speed. Preferably the ratio of gear reduction is sufficiently great enough to provide that when the supply of motive fluid to the motor is interrupted the drum will be unable to turn, owing to the impossibility of it driving the gearing, and in this way it will be noted a self-locking reduction gear connecting the motor and drum is secured. I have found that this condition 85 is satisfactorily provided for by forming the series 99 and 93 respectively of fourteen and thirty-four $7\frac{7}{23}$ -pitch teeth and the series 101 and 87 respectively of fourteen and thirty-two 7-pitch teeth. 90

In the present example of my invention, to permit the drum to rotate independently of the gearing, the gear 92 is capable of longitudinal movement relative to the pillar and carries a series of spaced jaws 102 100 adapted to mesh with the spaced jaws 105 carried by the drum, thus forming a disengageable clutch connection between the latter and the gear. The gear 92 is formed with an annular groove 107, which engages the lugs 109 integrally formed on the ends of the pair of clutch actuating shipper rods 111. For receiving the shipper rods, the pillar is provided with the slots 113, which are formed on diametrically opposite sides 110 of the surface of the pillar and extend to adjacent the outer end thereof, where the shaft is cut away to form the end slot 115 for receiving the shipper operating block 117. For securing the rods to the block, the end portions of the former are provided with the projections 119 fitting into end slots 121 of the block and are secured to the block by means of pins 123. The block is provided with a stem 125, to which is secured 120 the operating handle 127.

In the present construction, for holding the clutch in its engaged and disengaged positions, the upper portion of the pillar 125 is provided with a bore 124 at opposite end portions of which are placed plungers 126 and between which is located the compression spring 128 acting to force the plungers outwardly. Each shipper rod is provided with a pair of depressions 130, one of which 129

is engaged by the pins in the position of the shippers in which the clutch is engaged and the other in the position in which it is disengaged.

5 As illustrated, to provide a bearing for the drum, over the end of the pillar is placed the sleeve 129 and for holding the drum in place I provide the cap 131 secured to the pillar by suitable screws 133, the cap 10 being of diameter greater than the pillar and having a thrust surface 135 for the end bearing 137 of the drum.

The lower portion of the drum is provided with a brake flange 139, around which 15 is placed the brake strap 141. For operating the brake, the strap is secured at opposite ends to nuts 143 and 145 respectively engaging the right and left hand screw threads formed on opposite ends of the bolt 20 147.

Providing a bearing surface for the bolt is a pair of spaced lugs 149 carried by the gear casing member 84, while longitudinal movement of the bolt is prevented by a collar 151 located between the opposed 25 surfaces of the lugs and secured to the bolt by means of a pin 153. A handle 155 is provided for operating the brake. The brake flange and lower portion of the drum serve to form part of the gear casing. For 30 forming a tight joint between the stationary gear casing member 84 and the brake flange, the end of the latter is caused to bear against the packing 156 carried by the adjacent part of the member 84 of the 35 casing.

For lubricating the machine, the drum is provided with an interior cavity 157 adapted to be filled with grease through the plug 159, while leading from the oil reservoir 7 40 of the pillar are suitable passages 161 leading to the gear case and passages 163 leading to the bearing for the carrier 65. The motor is lubricated by lubricant conveyed by suitable passages 165, in communication 45 with the bearing of the gear carrier, the passage 165 communicating with the top and bottom surfaces of the central rotor by means of passages 167.

Although I have described one specific 50 embodiment of my invention it is to be understood that I am not limited thereby and that wide deviations may be made therefrom without departing from the spirit of my invention.

55 I claim:—

1. In a device of the character described, a drum, a fixed gear axially aligned with said drum, a second gear rotatable with said drum, a pinion meshing with said fixed 60 gear, a second pinion connected for simultaneous axial rotation with said first pinion and meshing with said second gear, said pinions and said gears forming two gear sets the difference in gear ratio of which is sufficient to render the train non-reversible,

a fluid pressure motor for rolling said first named pinion around said fixed gear to cause rotation of said drum, a non-rotatable pillar, said drum being rotatably mounted on one end of said pillar, said pillar at its 70 end opposite said drum having means for detachably connecting it to a mine column or the like, said motor being carried by said pillar between said means and said drum, said gears being carried between said motor and said drum, a casing for said motor, a brake flange carried by said drum and cooperating with said motor casing to form a chamber for said gears and pinions, a clutch for connecting or disconnecting 80 said second gear to or from said drum, a rod extending through said drum for operating said clutch, and handle means for operating said rod, said drum extending beyond the end of said pillar and surrounding 85 said handle means.

2. In a capstan, the combination with a drum, of planetary gearing involving a planetary gear carrier for driving said drum, a fluid pressure motor having a pair 90 of rotary members for forming an expandable chamber, said motor driving said planetary gearing, one of said rotary members being directly connected to said gear carrier, gearing connecting said gear carrier with the other of said rotary members for timing one rotary member with the other, said last named gearing comprising a ring carried by said carrier, said ring 95 having external gear teeth and surrounding 100 said planetary gearing.

3. In a device of the character described, a drum, a gear for driving said drum, a fixed gear coaxial with the first named gear, planetary pinions meshing with said gears, 105 a rotatable gear supporting and surrounding said pinions and being coaxial with the two first mentioned gears, a pillar on which said drum is mounted, said pillar surrounded by said rotatable gear, a fluid 110 pressure motor having cooperating rotary elements forming an expandable chamber, one of said rotary elements being geared to said rotatable gear, and the other being coaxial with said gears, a driving shaft rotatably supported by said pillar, said shaft being fixed to the rotary motor element which is coaxial with said gears and operatively connected in driving relation to said 115 rotatable gear, a casing for said motor, and means for attachment to a support for the device, said casing and pillar being operatively connected in fixed relation to said means.

4. In a device of the character described, 120 a drum, a gear for driving said drum, a fixed gear coaxial with the first named gear, planetary pinions meshing with said gears, a rotatable gear supporting and surrounding said pinions and being coaxial 125

with the two first mentioned gears, a fluid pressure motor having cooperating rotary elements forming an expansible chamber, one of said rotary elements being geared to said rotatable gear and the other being coaxial with said gears and directly connected to the rotatable gear.

5. In a device of the character described, a drum, a reduction gearing for driving said drum comprising an annular externally toothed gear member, planetary pinions surrounded and carried by said gear member, a fluid pressure motor having a pair of rotary elements acted upon by the motive fluid for converting the energy of the pressure fluid into work, said members having axes on opposite sides of the axis of said gear member, a gear connection between both of said rotating members and said annular gear member, a pillar rotatably supporting said drum and annular gear member, a casing for said motor, and means for detachable attachment to a support for the device, said casing and pillar being operatively connected in fixed relation to said means.

6. In a device of the character described, a pillar having means adapting it to be detachably connected at one end to a mine column or the like, a drum supported at the opposite end of said pillar, a rotary engine arranged adjacent to the first mentioned end of said pillar and having a rotor rotating about and concentrically arranged with said pillar, gearing between said engine and said drum and coaxial with said pillar, said gearing comprising planetary gears and a planetary gear carrier having a sleeve rotatably mounted on said pillar, said sleeve carrying said rotor, a gear carried by said planetary gear carrier, and rotary motor members cooperating with said rotor geared to said gear.

7. In a device of the character described, a pillar, a drum supported at one end of said pillar, a rotary engine at the opposite end of said pillar, said last mentioned end having means for detachably fastening said pillar to a mine column or the like, said engine having a rotor coaxial with said pillar, gearing between said engine and drum and coaxial with said pillar, a clutch for connecting said gearing to said drum, means extending through said drum for operating said clutch, handle means at the free end of said pillar for operating said clutch, and said handle means being located interiorly of said drum.

8. In a device of the character described, a pillar having at one end means for attachment to a mine column, a rotary engine having a rotor coaxial with said pillar and located adjacent said means, a drum mounted for rotation on the end of said pillar opposite said means, gearing between said engine

and drum, a clutch for connecting said gearing to said drum, and manually operated means located interiorly of said drum at the end of the drum remote from said first mentioned means for operating said clutch.

9. In a capstan, the combination with a drum, of a fluid pressure motor arranged adjacent to one end of said drum, planetary gearing operatively connecting said drum and motor, said planetary gearing including a planetary gear carrier for driving said drum, said fluid pressure motor having a pair of cooperating rotary motor elements for driving said planetary gearing, one of said elements being directly connected to said carrier to move conjointly therewith, gearing operatively connecting said planetary gear carrier with the other of said elements for timing one element with the other, said last named gearing comprising an annular externally toothed member surrounding said planetary gearing and a pinion secured to rotate with said other element and meshing with the external teeth of said annular member.

10. In a device of the character described, a drum, a non-rotating cylindrical support for said drum, a driving member, a clutch for connecting said driving member to said drum and located between the two, means extending through said drum for operating said clutch, and grooves formed on the exterior of said support for receiving said means.

11. In a device of the character described, a drum, a cylindrical support for said drum, a clutch at one end of said drum and surrounding said support, a shipper rod extending through said support from the opposite end of said drum and having means of attachment to said clutch, and operating means for said rod carried exteriorly of said support and contained substantially within the end of said drum opposite the clutch.

12. In a device of the character described, a pillar, a drum supported on the end of said pillar, a clutch element formed on said drum, a driving gear for said drum rotatably mounted on said pillar and having a clutch element for engagement with that of said drum, a shipper rod extending through said pillar, means affording a connection between said gear and rod, and operating means at the end of said drum opposite said gear for operating said rod.

13. In a device of the character described, a pillar, a drum supported on the end of said pillar, a clutch element formed on said drum, a driving gear for said drum rotatably mounted on said pillar and having a clutch element for engagement with that of said drum, a shipper rod extending through said pillar, means affording a connection between said gear and rod, operating means at the end of said drum opposite said gear for op-

erating said rod, and means carried by said pillar for holding said rod in its adjusted positions.

14. In a mine capstan, a motor having a non-rotatable casing, a drum exteriorly of said motor, a gearing between and connecting said motor and drum, said gearing comprising an external driven gear carried by said drum, a flange separate from said gearing carried by said drum, said flange extending within and substantially contacting said casing and in conjunction with said casing and drum forming a closed chamber serving to encase said gearing, and a friction member cooperating with said flange.

15. In a mine capstan, a motor, a drum, a gearing connecting said motor and drum, said gearing comprising an externally driven gear separably carried by said drum, a stationary gear casing portion carried by said motor, and a rotatable gear casing member separate from said gearing, and surrounding said external gear, said casing member being carried by said drum and cooperating with said stationary portion for completely encasing said gearing.

16. In a capstan, a pillar having at one end thereof means for detachably attaching it to a mine column or the like, said pillar having a drum thereon at the free end thereof and a motor at the opposite end thereof geared to said drum, said motor surrounding said pillar, means at the free end of said pillar for controlling the rotation of said drum, and said drum extending beyond the free end of said pillar and surrounding said last mentioned means.

17. In a capstan, a pillar having at one end thereof means for detachably attaching it to a mine column or the like, said pillar having a drum thereon at the free end thereof and a motor at the opposite end thereof geared to said drum, said motor and its gearing surrounding said pillar, manually operated means at the free end of said pillar for controlling said gearing, and said drum extending beyond the free end of said pillar and surrounding said last mentioned means.

18. In a capstan, means for attaching said capstan to a mine column or the like, said capstan comprising a pillar with a drum thereon at one end thereof, a motor surrounding said pillar at its other end, reduction gearing between and connecting said motor and drum, a clutch comprising a member rotatably and slidably mounted on said pillar for disconnecting the drum and gearing, clutch operating means at the end of the pillar carrying the drum, and connecting means extending through said pillar from said clutch operating means to said clutch.

19. In a capstan, a motor comprising a rotary piston and a cooperating rotary abutment at the side of said rotary piston, a drum aligned with said rotary piston, a

planetary gearing for connecting said motor and drum comprising a gear carrier driven by said rotary piston and carrying planetary pinions, external gear teeth on said carrier surrounding said pinions, and a pinion carried by said rotary abutment meshing with said external gear.

20. In a capstan, a motor comprising a rotary piston and a cooperating rotary abutment, a drum aligned with said rotary piston, a gear carried by said drum, a fixed gear, a planetary pinion member meshing with both of said gears, a carrier for said pinion member driven by said piston, and gearing comprising a gear surrounding said pinion member for connecting said carrier and rotary abutment.

21. In a capstan, a motor, a drum aligned with and exterior to said motor, gearing between said motor and drum, a clutch for detachably connecting said motor and drum, a frusto-conical member for attaching the motor end only of said capstan to a mine column or the like, and means at the opposite end of said capstan for operating said clutch.

22. In a capstan, a motor, a pillar coaxial with said motor and projecting therefrom, a drum on said pillar, gearing connecting said motor and drum, and said pillar having formed integrally therewith at the motor end thereof a frusto-conical portion for attaching said capstan to a mine column or the like.

23. In a capstan, a cylindrical pillar having formed integrally therewith at one end a frusto-conical extension for attaching it to a column, a drum mounted on the opposite end of said pillar and provided with clutch elements, a motor surrounding said pillar adjacent said frusto-conical extension, gearing between said motor and drum, said gearing having a gear surrounding said pillar and formed with clutch elements for engaging the clutch elements on said drum, a clutch operating member at the end of said pillar opposite said extension, and connecting means extending through said pillar for enabling said clutch operating member to slide said gear longitudinally of said pillar.

24. In a capstan, a pillar, a motor having a rotary piston surrounding said pillar, an abutment for said piston, a planetary gear carrier having a ring portion with external gear teeth, a pinion carried by said abutment and meshing with said external gear teeth, a gear fixed to said shaft, a gear rotatable on said shaft, means comprising planetary pinions surrounded by said ring portion for connecting said fixed and rotatable gears, and a drum on said pillar connected to said rotatable gear.

25. In a capstan, a pillar having a planetary pinion carrier rotatably mounted thereon, a gear fixed to said pillar, a gear rotatable on said pillar, planetary pinion means

rotatably supported on said carrier and connecting said gears, said planetary pinion carrier having an external gear surrounding said fixed gear, a motor element rotatable 5 with said carrier and a cooperating motor element geared to said external gear, a casing for said motor elements, a drum on said pillar connected to said rotatable gear, and said drum having a flange cooperating with 10 said motor casing to form a gear casing, and said flange surrounding said rotatable gear.

26. In a device of the character described, a drum, planetary gearing arranged adjacent to one end of said drum and involving a 15 planetary gear carrier for driving said drum, a fluid pressure motor directly associated with said planetary gearing and having a pair of rotary motor elements for driving said planetary gearing, one of said rotary 20 motor elements being connected to rotate with said planetary gear carrier, gearing

connecting said planetary gear carrier and the other of said rotary motor elements for timing one rotary motor element with the other, said last named gearing comprising a ring carried by said carrier surrounding said planetary gearing and having external teeth. 25

27. In a device of the character described, a drum, a gear for driving said drum, a fixed gear coaxial with the first named gear, planetary pinions meshing with said gears respectively, a rotatable gear supporting and surrounding said pinions and lying coaxial with the first two mentioned gears, a fluid pressure motor having a pair of cooperating rotary motor elements, one geared to said rotatable gear and the other coaxially arranged with respect to said gears. 30 35

In testimony whereof, I have signed my name to this specification.

GEO. H. GILMAN.
